UNITED STATES PATENT OFFICE.

SILAS R. DIVINE, OF LOCH SHELDRAKE, NEW YORK, ASSIGNOR TO THE
REND ROCK POWDER COMPANY, OF NEW JERSEY.

EXPLOSIVE COMPOUND.

SPECIFICATION forming part of Letters Patent No. 289,760, dated December 4, 1883.

Application filed August 1, 1883. (No specimens.)

To all whom it may concern:

Be it known that I, SILAS R. DIVINE, of
Loch Sheldrake, Sullivan county, State of New
York, and a citizen of the United States, have
5 invented an Improved Explosive Compound,
of which the following is a full, clear, and exact
specification.

My invention consists in an explosive compound, chiefly for blasting purposes, composed
10 of a solid ingredient—such as chlorate of potash—and a liquid ingredient—such as oil of
turpentine—the said ingredients being in themselves incapable of being exploded by percus-
sion, and, when mechanically united, forming
15 the explosive.

The theoretical proportions in which the ingredients of my explosive combine most effect-
ively are about eight and one-third parts of
chlorate of potash to one part of turpentine;
20 but inasmuch as turpentine possesses a strong affinity for oxygen, it may be desirable sometimes, when said turpentine, which is aged or has been more or less exposed to the air and has thus become oxidized, is employed as the liquid
25 ingredient, to avoid an unnecessary preponderance, and hence waste, of oxygen in the finally-prepared compound by decreasing the

proportion of the chlorate of potash, and thus varying somewhat from the exact theoretical proportions as stated.

3c

It will be understood that either perchlorate or permanganate of potash may be employed as the solid ingredient of my compound.

The ingredients of my compound being in-
explodible by themselves by percussion, they 35
may be separately handled and transported
with safety, and the consumer can unite them,
when and where it is desired to use the ex-
plosive, by either mixing them in measured
proportions in a suitable vessel or by simply 40
causing the solid to absorb the liquid.

What I claim as my invention, and desire to secure by Letters Patent, is—

The described explosive compound, com-
posed of a solid ingredient consisting of chlo- 45
rate of potash, and a liquid ingredient consist-
ing of turpentine, mechanically united, sub-
stantially in the proportions and as and for
the purposes specified.

SILAS R. DIVINE.
